US0D1035160S

(12) **United States Design Patent** (10) Patent No.: **US D1,035,160 S**
(45) Date of Patent: ** Jul. 9, 2024

(54) **SAFETY HELMET**

(71) Applicant: **CEIA—CENTRO DE
ENGENHARIA E
DESENVOLVIMENTO
(ASSOCIAÇÃO)**, Matosinhos (PT)

(72) Inventors: **Joana dos Santos Canossa**, Matosinhos (PT); **Helena Luísa Simas Silva**, Linda-a-Velha (PT); **José Rui de Encarnação Palma Felizardo**, Lisbon (PT); **José Roque Correio de Oliveira e Silva**, Oliveira de Azeméis (PT); **Bruno José Pinto Oliveira**, V.N. Gaia (PT); **Henrique Fonseca Alves Pimentel**, Coimbra (PT); **Jorge Miguel Silva Carneiro**, Matosinhos (PT); **Luís André Mestre Leitão**, Oporto (PT); **Paulo Fernando Gonçalves da Encarnação**, Matosinhos (PT); **Pedro Miguel de Azinheira Reguenga**, Santo Tirso (PT); **Gustavo Seixas de Sá Burmester**, Matosinhos (PT)

(**) Term: **15 Years**

(21) Appl. No.: **35/515,615**

(22) Filed: **Jul. 8, 2022**

(80) **Hague Agreement Data**

Int. Filing Date: **Jul. 8, 2022**

Int. Reg. No.: **DM/224707**

Int. Reg. Date: **Jul. 8, 2022**

Int. Reg. Pub. Date: **Nov. 18, 2022**
